(57) **CLAIM**

The ornamental design for a combination cylindrical cooler cover and cooler lid cover, as shown and described.

DESCRIPTION

FIG. 1 is a perspective view of the cylindrical cooler cover and cooler lid cover design in a lid-closed position;

FIG. 2 is a front view of the cylindrical cooler cover and cooler lid cover design;

FIG. 3 is a rear view of the cylindrical cooler cover and cooler lid cover design;

FIG. 4 is a left side view of the cylindrical cooler cover and cooler lid cover design;

FIG. 5 is a right side view of the cylindrical cooler cover and cooler lid cover design;

FIG. 6 is a top view of the cylindrical cooler cover and cooler lid cover design in a lid-closed position;

FIG. 7 is a bottom view of the cylindrical cooler cover and cooler lid cover design; and,

FIG. 8 is a perspective view of the cylindrical cooler cover and cooler lid cover design in a lid-open position, the interior of the lid is unadorned.

The phantom lines showing environment are for illustrative purposes only.
